Primary Examiner — Celia Murphy*Assistant Examiner* — John Reickel(74) *Attorney, Agent, or Firm* — Andrew W. Chu; Craft Chu PLLC(57) **CLAIM**

The ornamental design for a bypass pipe joint, as shown and described.

DESCRIPTION

FIG. 1 is an upper perspective view of the bypass pipe joint showing my design as installed in a curved pipe with probes in broken lines.

FIG. 2 is a top plan view thereof;

FIG. 3 is a bottom plan view thereof;

FIG. 4 is a side elevation view thereof;

FIG. 5 is an opposite side view thereof;

FIG. 6 is a front elevation view thereof;

FIG. 7 is a back elevation view thereof; and,

FIG. 8 is still another perspective view, showing the bypass pipe joint mounted on a storage tank in broken lines.

The broken line showing of the curved pipe, probes, and storage tank is included for the purpose of illustrating environmental structure and forms no part of the claimed design.
